(57) **CLAIM**

I claim the ornamental design for a paintbrush holder, as shown and described.

DESCRIPTION

FIG. 1 is a front view of the paintbrush holder.

FIG. 2 is a rear view of the claimed design.

FIG. 3 is a left side view of the claimed design.

FIG. 4 is a right side view of the claimed design.

FIG. 5 is a top view of the claimed design.

FIG. 6 is a bottom view of the claimed design; and,
FIG. 7 is a perspective view of the claimed design as appears on a paint can.

The broken lines appearing on FIG. 7 of a paint can and paintbrush are environmental matter forming no part of the claimed design.
